UNITED STATES PATENT OFFICE.

ERNEST J. BRASSEUR, OF CHICAGO, ILLINOIS.

MEMORANDUM DEVICE.

Application filed June 22, 1920. Serial No. 390,722.

To all whom it may concern:

Be it known that I, ERNEST J. BRASSEUR, a citizen of the United States, residing in the city of Chicago, county of Cook, and 5 State of Illinois, have invented certain new and useful Improvements in Memorandum Devices, of which the following is a specification.

My invention relates to memorandum devices by which business or engagements, which should be attended to on certain dates, may readily be presented to the attention of the proper person. I accomplish this by means of a form of calendar device in 15 which the days of the current month are presented to the eye of the user, together with memorandum tabs, which are removably secured in alignment with different dates. When an engagement for a future 20 month is to be noted, the calendar device is moved into position to insert an appropriate tab in the appropriate location whereupon the calendar device may again be put into the appropriate position for the current 25 month.

The memorandum tabs are preferably designated by letters which may designate individuals or companies with which certain engagements are concerned. Upon the 30 arrival of a day at the indication of which a tab is secured, the user may refer to the record files, which are preferably stored in the back of the casing in which the calendar device is located.

35 The files may comprise jackets or folders, one for each letter of the alphabet, each jacket preferably being subdivided as by partition sheets, into sub-compartments, each of which is preferably reserved for a particular date designation. The movable calendar device carries designations of the months, in 40 spaced relation, and preferably carries the names of the days of the week in series, these days of the week aligning, when a particular month strip is brought into view, with designations of the days of the month 45 which may be printed upon the face of the casing. The strips bearing the days of the week are adjustably mounted so that 50 the calendar may be reset each year to bring the days of the week into alignment with the days of the month which coincide with the days of the week.

In accordance with the above, on Thursday, June 10th, for example, the user may 55 find an A tab inserted in alignment with the

designation "Thursday" on the movable carrier of the calendar device and likewise in alignment with the designation "10" on the casing. On this date he removes the tab and 60 turns to the "A" jacket in his record file and opening the same to the subdivision marked "Thursday" finds the data or records to which the memorandum refers, together, perhaps, with other papers. When 65 the matter has been attended to the papers may be removed, or if they again require attention on some fixed future date, they may be replaced in the compartment appropriate to such date and the memorandum 70 tab again positioned in alignment with such future date on the calendar device.

I preferably produce the effects referred to by the provision of a rotatable carrier, preferably a drum, mounted within a casing 75 having a window therein. Channel strips are mounted about the drum with spring devices therein for removably securing the memorandum tabs. Strip holders are secured to the longitudinal edges of the channel shaped members referred to and calendar strips mounted therein, certain strips bearing the designations of the days of the week and other strips bearing the names of the various months. Numerals 1 to 31 are 85 displayed on the face of the casing adjacent to the window. The days of the week strips contain the designations of 31 or more days of the month and are arranged to be bent under at one or both ends, at different distances from the ends, when they are mounted in their holders, so as to properly align the days of the week of each month of the current year with the days of the month 1 90 to 28 or 30, 31, &c.

In order that a clearer understanding of my invention may be had, attention is hereby directed to the accompanying drawings forming part of this application and illustrating one embodiment of my invention. In 100 the drawings Fig. 1 represents a front elevation of apparatus comprising my invention, certain parts being broken away and certain parts being shown in vertical section, Fig. 2 is a top plan view of the apparatus, 105 Fig. 3 is a vertical section taken on lines 3—3 of Fig. 2, Fig. 4 represents a side elevation of one of the channel strips used in the construction of the apparatus with the spring holders thereof secured thereto, Fig. 5 is a cross section taken on line 5—5 of Fig. 4, Fig. 6 is a top plan view of the ele- 110

- ments shown in Fig. 4, Figs. 7 and 8 are respectively partial side elevations of the channel member and a spring holder member therefor, separated from each other, Fig. 9 is a plan view of one of the calendar strips, Fig. 10 is a similar view of one of the month strips, Fig. 11 is a plan view of a holder for the strips shown in Figs. 9 and 10, Fig. 12 is a plan view of one of the memorandum tabs, Fig. 13 is a plan view of the current date indicator, Fig. 14 is a front elevation of one of the separator sheets for the jackets in the filing cabinet and Fig. 15 is a front elevation of one of the jackets in the filing cabinet.
- 15 Referring to the drawings, the device illustrated comprises a base 1 on which is mounted a casing 2 having a vertical front portion 3 and upwardly and rearwardly sloping portion 4, a horizontal portion 5 to the rear of portion 4, an upwardly extending portion 6 to the rear of portion 5, and a rear portion 7. A window 8 is formed in the sloping portion 4 of the casing. The casing 2 is provided with end portions designated generally as 9, 9. The filing compartment may be provided to the rear of casing 2 between the rear wall 7 of casing 2, the wall 10 adjacent the rear of the base 1 and the end walls designated at 11, 11.
- 30 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 45 The stub shafts 14, 14' may conveniently be rotatably supported by members 9' which are secured to the end members 9 of the casing. The handle member 16 may be provided with a ratchet wheel 17 with which the spring-pressed pawl 18 engages to provide means for holding the drum non-positively in any adjusted position.
- 50 The discs 13 are given an irregular peripheral shape, shoulders being provided upon which the channel members 19 are mounted. Each channel member is bent from a single strip of sheet metal so as to provide a forward flange 20 a web portion 21 and a rear flange 22, which is preferably of less height than flange 20. The upper edge of flange 20 is bent forwardly to form an edge flange 23 and the upper edge of flange 22 is bent rearwardly to form an edge flange 24.
- 55 Each forward flange 20 is provided with a longitudinal series of openings 25 there-through, these openings preferably being formed by slotting the metal and bending the metal included within the slotted-out portion rearwardly to form short rearwardly directed flanges 26, each of the same being at the right of its opening 25, referring to Figs. 4 and 7.
- 60 Fig. 13 is a plan view of the current date indicator, Fig. 14 is a front elevation of one of the separator sheets for the jackets in the filing cabinet and Fig. 15 is a front elevation of one of the jackets in the filing cabinet.
- 65 Referring to the drawings, the device illustrated comprises a base 1 on which is mounted a casing 2 having a vertical front portion 3 and upwardly and rearwardly sloping portion 4, a horizontal portion 5 to the rear of portion 4, an upwardly extending portion 6 to the rear of portion 5, and a rear portion 7. A window 8 is formed in the sloping portion 4 of the casing. The casing 2 is provided with end portions designated generally as 9, 9. The filing compartment may be provided to the rear of casing 2 between the rear wall 7 of casing 2, the wall 10 adjacent the rear of the base 1 and the end walls designated at 11, 11.
- 70 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 75 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 80 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 85 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 90 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 95 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 100 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 105 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 110 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 115 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 120 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 125 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.
- 130 The calendar device, in the form of construction illustrated herein, comprises a rotatable drum or carrier. This may be formed by the provision of a tube 12 which is secured to or integral with a number of spaced discs 13. Stud shafts 14, 14' are secured within the opposite ends of the tube 12 and are rotatably mounted in the end members of casing 2. Stud shaft 14 is provided with an end portion 15 of reduced diameter to which the handle member 16 is secured, this handle member preferably taking the form of a knurled knob. The knurled knob 16' is similarly mounted on the opposite end of the construction so that the drum may be operated from either end.

may be substantially the outline shown in Fig. 3 by the inner outline of the channel members and the strip holders connecting the same together. Channel members 5 mounted as described extend in substantially tangential directions about the drum.

A calendar strip 39 is mounted in each strip holder 37. Each strip 39 may be formed of paper, or other flexible material, 10 having the days of the week, Monday, Tuesday, Wednesday, etc., printed thereon in a continuous series of a length sufficient to provide thirty-one or more day designations.

A strip 39 is inserted in its holder and a 15 month strip 40 is inserted in the same holder 37 above the strip 39. The month strips are celluloid or other suitable transparent material, so that the days of the week carried on the strip 39 are visible therethrough. 20 Each of these month strips carry the name of one of the months, January to December. Preferably, the strip 39 carries the names of the days of the week along the top of the strip, and the strips 40 carry the names of 25 the month at the bottom of the strip, so that the names of the days of the week and the name of the month will be both clearly visible. The width of strips 39 and 40, if desired, may be so chosen that these strips 30 occupy respectively the upper and lower half of the channel of strip holder 37 as shown in Fig. 2. With this arrangement strip 40 need not be transparent.

The numerals 1 to 31 are printed, as is 35 shown at 41, in a continuous series on the face of the sloping portion 4 of the casing immediately above the window 8. These day of the month indications are preferably 40 printed on a suitable strip which is held within a channeled holder 42. Members 43, 43, are provided at the ends of window 8, being secured in position by screws 44 which 45 extend into the inner frame member 45 of the casing which may be provided at the ends of the structure to extend parallel with the portions 3, 4 and 5 of the casing 2. Pins 46 may be used to secure the day of the month strip holder in position.

A small indicator 47 of colored celluloid 50 or other suitable light transmissive material may be slidably mounted in holder 42 so that the same may be manually adjusted to indicate the current date, or any other time, if desired.

The memorandum tabs 48 may be formed 55 of pasteboard or the like and preferably have the letters A, B, C, etc. printed thereon. Any tab may be inserted in position between the portion 32 of any spring tongue 60 and the flange 22 of a channel member indicated thereby.

The tabs are preferably kept, when not 65 in use, in proper order in a suitable rack or receptacle. As shown a channel strip 49 may be secured to the upper vertical

portion 6 of the casing, holder 49 containing a strip 50 having printed thereon the letters of the alphabet in succession. Immediately below the same a channeled member 51 may be positioned. This member 70 may be entirely similar to the channel members 19 previously described and may have a spring member similar to the spring members described in connection with channel members 19, associated therewith. This 75 spring member has spring tongues 52 extending through openings in the flange 53 of the channel member engaging against the flange 54 of the chamber member. The various tabs 48 may be held in position for 80 use by inserting the same between spring tongues 52 and flange 54, in alignment with the corresponding letters of the alphabet printed on strip 50. The channel member 51 may be mounted in position by inserting 85 the same through an opening 55 in the top flange 5 of the casing.

The calendar strips 39 may be bent under at the ends on any desired folding lines such as are indicated at 56 in Fig. 9 when the 90 device is adjusted for a different year. Each strip holder 37 with strips 39 and 40 carried thereby may be withdrawn through an opening 57 in one of the end walls of the casing, the drum being rotated to align the 95 strip holders successively with this opening. The strips 39 are then bent so that the proper day of the week will align with the numeral 1 of the day of the month strip 41, and so that the strip 39 will not extend 100 further to the right than a position in alignment with the last day of that particular month such as 28, 30 or 31. The strip 39 is then re-positioned in its holder with its month strip 40 above the same and the 105 holder is again re-placed in position.

In the operation of the device the drum may be rotated by knob 16 until the current month, for example December, is visible at the window 8. Any memorandum tabs 110 which have been positioned in alignment with dates in December will likewise be visible at the window, for example, the "A" tab shown in the drawings as in alignment with the date indications for Saturday the 115 4th. It will be obvious that any desired number of tabs may be inserted in alignment with any date indication. On Saturday the 4th the "A" tab shown may be removed and re-placed in the holder for A 120 tabs at the left of the channel frame 51.

The data or correspondence indicated by this "A" tab may then be consulted. The record files are preferably held in the casing at the rear of frame member 7 as stated. 125 Preferably a plurality of jackets similar to that shown at 57' in Fig. 15 are provided, one for each letter of the alphabet, these jackets being separated by index sheets 58 each having a designating letter thereon. 130

Preferably, the jackets 57' are divided into compartments each of which may be used for records to be taken up on a particular day of the week, these compartments 5 being separated by sheets 58' which may be labeled with abbreviations for the days of the week. The data referred to by the particular tab 48 shown in the drawings should be placed in the "A" jacket in the 10 sub-division thereof reserved for matters to be attended to on Saturday. Other filing arrangements may, of course, be used but the above system is thought preferable.

It should be understood that my invention 15 is not limited strictly to the detail of construction described but is as broad as is indicated by the accompanying claims.

What I claim is:

1. In a memorandum device, the combination of a frame having a window therein, a carrier rotatably mounted in said frame, means for indicating the names of the month about said carrier in spaced relation, means on said frame adjacent said window 25 for indicating in serial order the days of a month, and means on said carrier adjacent said month indications for removably holding memorandum tabs in positions which will align the same with desired day 30 indications when the adjacent month indication is aligned with said window, said carrier being arranged to align with said window any month indication together with the tabs carried adjacent thereto.

2. In a memorandum device, the combination of a frame having a transversely extending window therein, a carrier supported by said frame and positioned to be progressed past said window, means for indicating the names of the months on said carrier, in spaced relation, means on said frame adjacent said window for indicating in order the days of a month, means on said carrier, adjacent said month indications, for removably holding memorandum tabs in positions which will align the same with desired day indications when the adjacent month indication is aligned with said window, and means for progressing said carrier and holding the same in position with any month indication and the tabs carried adjacent thereto, in alignment with said window.

3. In a memorandum device the combination of a frame having a transversely extending window therein, a carrier supported by said frame and positioned to be progressed past said window, means for indicating the names of the months across said carrier, in spaced relation lengthwise thereof, and the days of the week in each month, adjacent the month indications, means on said frame adjacent said window 65 for indicating thirty-one days in order, and

means on said carrier for removably holding memorandum tabs in alignment with any week day indications, said carrier being arranged to align with said window any month indication together with the tabs 70 carried adjacent thereto, said week day indications being arranged to properly align, for any year, with the corresponding day of the month indications on the frame.

4. In a memorandum device the combination of a rotatable carrier, a frame supporting the same, strip holders carried by said carrier, successively, one for each month, and strips mounted for longitudinal adjustment in said strip holders, each having 80 printed thereon the days of the week for more than four weeks, said strips being adapted to have their end portions bent under.

5. In a memorandum device, the combination of a rotatable carrier, a frame supporting the same, strip holders carried by said carrier, successively, one for each month, strips mounted in said strip holders, each having printed thereon successively the days 90 of a month, and spring means for removably holding memorandum tabs in alignment with any day designation.

6. In a memorandum device, the combination of a rotatable carrier, a frame supporting the same, strip holders carried by said carrier, successively, one for each month, calendar strips of flexible material, each having printed thereon the days of the week for more than four weeks, mounted 100 for longitudinal adjustment in said holders, and transparent strips mounted in said holders above said calendar strips, each bearing the designation of a different month.

7. In a memorandum device, the combination of a rotatable carrier, metal strips extending transversely across the same, each bent in channel shape, with the longitudinal edges of the strips bent forwardly and rearwardly respectively and calendar strip 105 holders positioned each against the forward edge flange of one, and the rearward edge flange of the next one, in advance, of said bent strips.

8. In a memorandum device, the combination of a rotatable carrier, metal strips extending transversely across the same, each bent in channel shape outwardly of the carrier, the forward flange of each channel strip having a series of openings there- 115 through with rearwardly directed flanges adjacent the openings, and springs inserted through said openings and pressing against the forward face of the rear flange of each channel strip, said strips being adapted to 120 support calendar strip holders.

9. In a memorandum device, the combination of a rotatable carrier, metal strips extending transversely across the same, each bent in channel shape outwardly of the car- 130

- rier, the forward flange of each channel strip having a series of openings therethrough with rearwardly directed flanges adjacent the openings, the longitudinal edges of the forward and rear flanges of the channel strips being bent forwardly and rearwardly respectively, springs extending forwardly and upwardly from the bottom of each forward flange, and then bent downwardly and rearwardly through said openings, to press against the forward face of the corresponding rear flange, and calendar strip holders mounted above the bent springs, with their forward and rear edges inserted beneath the rear and forward edge flanges of adjacent channel strips.
10. In a memorandum device, the combination of a rotatable carrier, a metal strip bent in channel shape, the forward flange thereof having a longitudinal series of openings therethrough, and a spring member having a base portion adapted to fit around the base of said channel strip, with flat spring portions extending forwardly and upwardly therefrom, and then bent rearwardly and downwardly to extend through said openings into contact with the forward face of the rear flange of the channel strip.
- 20 11. In a memorandum device, the combination of a rotatable drum, channel members
- 5 adjacent the openings, the longitudinal edges of the forward and rear flanges of the channel strips being bent forwardly and rearwardly respectively, springs extending forwardly and upwardly from the bottom of each forward flange, and then bent downwardly and rearwardly through said openings, to press against the forward face of the corresponding rear flange, and calendar strip holders mounted above the bent springs, with their forward and rear edges inserted beneath the rear and forward edge flanges of adjacent channel strips.
12. In a memorandum device, the combination of a rotatable carrier, a casing therefor, a channel frame secured to said casing, one flange of said frame having a longitudinal series of openings therethrough, and springs secured to said channel frame and extending through said openings to engage the opposite flange to form spring holders for memorandum tabs.
13. In a memorandum device, the combination of a casing, movable calendar indicia therein, having month designations and day designations for each month, lettered memorandum tabs, means for removably holding the same adjacent to each day designation, and correspondingly lettered data jackets in said casing and having sub-divisions corresponding to said day designations.
- 25 30 This specification signed and witnessed this 18th day of June, 1920.
